(57) **CLAIM**

The ornamental design for a chassis of electric wheelchair,
as shown and described.

DESCRIPTION

The patent or application file contains at least one drawing
executed in color. Copies of this patent or patent application
publication with color drawing(s) will be provided by the
Office upon request and payment of the necessary fee.

1. Chassis of electric wheelchair

1.1 : Front

1.2 : Back

1.3 : Right

1.4 : Left

1.5 : Top

1.6 : Bottom

1.7 : Perspective

In the reproductions, the blue-colored portions of the chassis
of electric wheelchair form no part of the claimed design.

1 Claim, 7 Drawing Sheets
